APPARATUS FOR CEMENTING WELLS

Harold E. Hough, Fairmont, W. Va.

Application April 15, 1936, Serial No. 74,488

10 Claims. (Cl. 166—19)

This invention relates to apparatus for cementing wells.

The primary object of the invention is to provide a device whereby a quick-setting cementitious material in a liquid or semi-liquid state may be lowered into an oil or gas well to a point where the wall of the well has caved in or become ruptured, the cement being released and discharged from the device under pressure at the predetermined point of cave-in in the well so that the cement may be sprayed therefrom, impinge and become lodged against the caving surface to a predetermined, substantially uniform, thickness for forming a lining for the ruptured or slipping portion which, when hardened or set, serves as a lining to prevent further caving or inward movement of the earth.

Another object of the invention is to provide a device of the character mentioned wherein the discharge of the cement may be accurately governed or controlled, no cement being discharged until the operator so desires.

A further object is to provide such a device wherein cement will not be discharged therefrom during lowering or elevating movements of the device in the well.

A still further object of the invention is to provide a device of the character mentioned which may be economically manufactured; inexpensive to repair, and which may be readily cleaned following use.

With these and other objects in view the invention resides in certain novel features of construction, operation and arrangement of parts which will hereinafter be fully described, reference being had to the accompanying drawings, in which—

Figure 1 is a vertical sectional view of a well illustrating the device positioned in a cave-in and the parts of the device being depicted in cement-spraying relation;

Figure 2 is a vertical sectional view of the device, the parts being depicted in non-discharging relation;

Figure 3 is a top plan detail view of the latch tripping member;

Figure 4 is a side elevational view of the same;

Figure 5 is an enlarged fragmentary vertical sectional view illustrating the latch mechanism adapted to normally maintain the discharge ports in non-registering position;

Figure 6 is an enlarged sectional view taken on line 6—6, Fig. 2;

Figure 7 is an enlarged sectional view taken 55 on line 7—7, Fig. 1; and—

Figure 8 is an enlarged sectional view taken on line 8—8, Fig. 5.

Referring to said drawings, the reference numeral 2 designates the head of the device consisting of a hollow cylindrical section of pipe which is designed to be detachably connected to a length of pipe or a well bailer 3 by means of the coupling 4, the pipe 3, which may be of any predetermined length or capacity, serving as a hopper or reservoir for containing the supply or charge of cementitious material. A carrying bail 5 is pivotally attached to the upper open end of the hopper 3 and is designed to receive a length of cable by means of which the apparatus is raised and lowered in the well casing 35.

Depending downwardly from the bottom 6 of the head 2 is a tube 7, the same being closed at its lower end by a weighted stopper ball 8 maintained in place by the pin 9, the tube 7, as will hereinafter be made manifest, serving as a discharge nozzle for the cement. Lateral discharge ports 10 are provided in the tube 7 at diametrical opposite points approximately midway of its length, although the number and position of said ports may be varied.

Slidable on the nozzle tube 7 is a sleeve 13, said sleeve having an annular flange 14 formed on its upper end and ports 15 in the side wall similar to the ports 10.

Threadedly received in the bottom 6 of the head 2 are the upper ends of two downwardly depending pins 16. Said pins 16 penetrate vertical apertures provided therefor in the sleeve flange 14, and each of said pins is encircled by opposed spiral compression springs 17, one such spring being interposed between the flange 14 and bottom 6, and the other being interposed between the flange 14 and the retaining nut 18. The springs, as above stated, oppose each other and are of equal strength and are designed so that the pressure exerted by the upper and lower springs on the flange 14 is equalized, thus to maintain the ports 10 of the nozzle tube 7 and the ports 15 of the sleeve 13 in registering aligned discharging relation, as illustrated in Figs. 1 and 7 of the drawings.

Also slidable on the nozzle tube 7 at a spaced distance below the sleeve 13 is a collar 19, said collar being connected to the annular flange 14 of the sleeve 13 by means of radially spaced bowed leaf springs 20, the opposite ends of the springs being received within recesses 21 provided therefor in the peripheries of the flange 14 and collar 19. Pins 22 secured by cotter pins retain the springs in place.

Locking mechanism for the device is afforded so as to maintain the ports 10 and 15 in non-registering non-spraying relation, as when the same is filled with cementitious material and the same is being lowered into the well. Said locking mechanism consists of a latch member 23 pivotally mounted on a pin 24 in a recess 25 provided in the bottom 6 of the head, said latch having a cut-out portion adapted to engage the flange 14 when the sleeve 13 is elevated upward against the tension of the two upper springs 17. The latch member 23 is maintained in inward flange-engaging position by means of a flat spring 26 interposed between the latch and an integral shield 27 depending from the head 2.

Trip mechanism for predeterminedly releasing the locking mechanism consists of a vertically extending trip lever 28 slidably received and supported within appropriate recesses 21 of the flange 14 and collar 19, pins 29 maintaining said trip lever 28 in position in said recesses. Formed integral with the upper extremity of the lever 28 is an angularly disposed dog 30 designed to occupy a position intermediate the latch 23 and the nozzle tube 7. Spaced lugs 32 are formed integral with the upper extremity of the lever and extend outwardly thereof to receive therebetween the upper end of a bowed leaf spring 20' (identical in construction with the springs 20), the lower end of said spring being rigidly attached to the lower end of the lever, as shown at 33.

In practice, the sleeve 13 is elevated against the tension of the two upper compression springs 17 to a point where the latch 23 engages the flange 14, thus to position the ports 10 and 15 in non-registering and non-spraying relation, the latter being disposed above the plane of the former, as shown in Figs. 2 and 5. Thus, no cement can be discharged from the nozzle tube 7.

A quantity of an appropriate cementitious material in a suitable liquid state is introduced into the reservoir 3 and thereafter the device is lowered into the well by the cable attached to the bail 5 until the spraying device reaches the point of cave-in 34. At this point it is now desired to discharge the cement, and discharge thereof is accomplished by elevating the device a distance wherein the bowed leaf spring 20' frictionally engages the restricted and smaller well casing 35. Further elevation of the device is resisted by the leaf springs 20 and 20' and as the latter contacts the well casing 35, it is depressed and, in turn, depresses the trip lever 28 to a point where its dog 30 forces the latch 23 out of locking engagement with the flange 14. Thus, the tension of the spiral compression springs 17 is permitted to be equalized thereby permitting the discharge ports to assume aligned spraying relation for allowing discharge of the cement.

The imposed weight of the cement in the reservoir results in considerable pressure at the ports so that the cement is sprayed with considerable velocity or pressure against the surface of the cave-in and tenaciously adheres thereto for effecting a lining of cement and preventing further objectionable slippage. As above stated, the cement is preferably quick setting so that it hardens with rapidity.

The device is preferably rotated and vertically reciprocated in the cave-in by means of the suspending cable in order that the entire surface of the cave-in may receive an adequate coating of cement.

After a sufficient coating of cement is applied, the device is withdrawn upwardly through the well through the casing 35. When the device during elevation enters the casing 35 the leaf springs 20 and 20' frictionally engage the defining wall and offer resistance to elevating movement. The resistance exerted by the leaf springs is insufficient to prevent continued elevation, but it is sufficient to overcome the tension of the two lower compression springs 17 and, as a consequence, the sleeve 13 is moved downwardly on the tube 7 to a point where the port 15 of the former is below and out of register with the port 10 of the latter. Thus, no cement can be discharged or released from the device while the same is being removed from the well.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is—

1. In a device of the character described, a reservoir for a quantity of cementitious material, a nozzle leading from said reservoir, a discharge port in said nozzle, a sleeve slidable on said nozzle and having a port, and spring means connecting said nozzle and said sleeve for normally maintaining said ports in registering and discharging alignment.

2. In a device of the character described, a reservoir for a quantity of cementitious material, a nozzle leading from said reservoir, a discharge port in said nozzle, a sleeve slidable on said nozzle and having a port, spring means connecting said reservoir and said sleeve for maintaining said ports in aligned discharging relation, and locking means suspended from said reservoir engageable with said sleeve upon upward movement of the sleeve on said nozzle whereby said ports may be maintained in non-aligned and non-discharging relation against tension exerted by said springs.

3. In a device of the character described, a reservoir for a quantity of cementitious material, a nozzle leading from said reservoir, a discharge port in said nozzle, a sleeve slidable on said nozzle and having a port, spring means connecting said reservoir and said sleeve for maintaining said ports in registering and discharging alignment, locking means suspended from said reservoir engageable with said sleeve upon upward movement of the sleeve on said nozzle whereby said ports may be maintained in non-registering relation against tension exerted by said springs, and release mechanism borne by said device whereby the locking means may be predeterminedly disengaged and rendered inoperative for permitting said ports to assume registering relation.

4. In a device of the character described, a reservoir for a quantity of cementitious material, a nozzle leading from said reservoir, a discharge port in said nozzle, a sleeve vertically slidable on said nozzle and having a port, spring means connecting said reservoir and said sleeve for maintaining said ports in registering and discharging alignment, locking means engageable with said sleeve in its elevated position on said nozzle whereby said ports may be maintained in non-registering relation against tension exerted by

said springs during lowering of the device into the well, tripping mechanism borne by said device whereby the locking means may be predeterminedly disengaged and rendered inoperative for 5 permitting said ports to assume registering relation, and resilient means independent of said first mentioned spring means frictionally engageable with the well casing whereby the sleeve is moved downward on the nozzle and said ports are made 10 to assume non-registering relation during withdrawal of the device from the well.

5. In a device for spraying the interior of wells consisting of a reservoir for the material to be sprayed, a discharge tube depending downwardly 15 from said reservoir and having lateral discharge ports, a sleeve having lateral ports and received about and slidably upon said tube, an annular flange formed about the periphery of said sleeve, and opposed equalized compression springs exerting a uniform pressure on the upper and lower 20 surfaces of said sleeve flange for maintaining the two sets of ports in registering and discharging aligned relation.

6. In a device for spraying the interior of wells 25 consisting of a reservoir for the material to be sprayed, a discharge tube depending downwardly from said reservoir and having lateral discharge ports, a sleeve having lateral ports and received about and slidably upon said tube, an 30 annular flange formed about the periphery of said sleeve, opposed equalized compression springs exerting a uniform pressure on the upper and lower surfaces of said sleeve flange for maintaining the two sets of ports in aligned and spraying 35 relation, and a latch member pivotally suspended from a fixed portion of the device and engageable with said flange whereby said ports, following upward movement of said sleeve on said tube, may be maintained in non-registering 40 relation against tension exerted by certain of the compression springs.

7. In a device for spraying the interior of wells 45 consisting of a reservoir for the material to be sprayed, a discharge tube depending downwardly from said reservoir and having lateral discharge ports, a sleeve having lateral ports and received about and slidably upon said tube, an annular flange formed about the periphery of said sleeve, opposed equalized compression springs exerting 50 a uniform pressure on the upper and lower surfaces of said sleeve flange for maintaining the two sets of ports in aligned and spraying relation, a latch member pivotally suspended from a fixed portion of the device and engageable with 55 said flange whereby said ports, following upward movement of said sleeve on said tube, may be maintained in non-registering relation against tension exerted by certain of the compression springs, and release mechanism including a 60 wedge trip dog engageable with said latch member upon actuation whereof the latch may be disengaged from said flange for permitting the sleeve to slide downward on the tube for positioning said ports in aligned and spraying relation.

8. In a device for spraying the interior of wells 65 consisting of an elongated reservoir for the material to be sprayed, a discharge tube depending downwardly from said reservoir and having lateral discharge ports, a sleeve having lateral 70 ports and received about and slidably upon said tube, pins depending downwardly from said res-

ervoir and encircled by opposed equalized compression springs exerting a uniform pressure on a contacting portion of the sleeve for maintaining the two sets of ports in registering aligned and spraying relation, a collar embracing said tube and spaced at a distance from said sleeve, a latch member pivotally suspended from a fixed portion of the device and engageable with said sleeve, when the latter is moved upwardly on said tube, whereby said ports may be maintained in 10 non-registering relation against the tension of certain of said compression springs during lowering movement of the device in the well, release mechanism consisting of a wedge trip dog engageable with said latch member whereby upon 15 actuation thereof the latch may be disengaged from said sleeve for permitting said sleeve to slide downwardly on said tube and to permit said ports to assume registering discharge relation at a predetermined point in the well, and bowed leaf springs connecting said collar and said sleeve having an axial diameter greater than 20 the diameter of the well and adapted to frictionally resist elevating movement of said device in the well for moving said sleeve and said collar 25 downwardly on the tube for positioning said ports again in non-registering relation during elevation of the device from the well.

9. In a device for spraying the interior of wells 30 consisting of a reservoir for the material to be sprayed, a nozzle leading from said reservoir, a discharge port in said nozzle, a sleeve 35 slideable on said nozzle and having a port similar to the port of said nozzle and in registering alignment therewith, resilient means extending outwardly from said sleeve and frictionally engageable with the well casing during vertical movements therein whereby said sleeve may be moved along said nozzle for a limited distance for affecting the relative positions of said ports 40 to each other, and opposed equalized compression springs suspended from said reservoir exerting a uniform pressure on a contacting portion of the sleeve for maintaining said ports in registering relation in the absence of frictional engagement of said resilient means with the well 45 casing.

10. In a device for spraying the interior of wells 50 consisting of a reservoir for the material to be sprayed, a nozzle leading from said reservoir, a discharge port in said nozzle, a sleeve 55 slideable on said nozzle and having a port similar to the port of said nozzle and in registering alignment therewith, resilient means extending outwardly from said sleeve and frictionally engageable with the well casing during vertical movements therein whereby said sleeve may be moved along said nozzle for a limited distance for affecting the relative positions of said ports 60 to each other, opposed equalized compression 65 springs suspended from said reservoir exerting a uniform pressure on a contacting portion of the sleeve for maintaining said ports in registering relation in the absence of frictional engagement of said resilient means with the well casing, and resilient means attached to a fixed portion of said device and engageable with said sleeve when the latter is moved along said nozzle toward the reservoir to maintain said ports in 70 non-registering relation.

HAROLD E. HOUGH.
